TWINE MAKING MACHINE

Harold Flater, Ernst Teodor Waernhoff, and Nils Gunnar Franson, Norrkoping, Sweden, assignors to International Harvester Company, a corporation of New Jersey

Application June 15, 1946, Serial No. 677,020
In Sweden June 25, 1945

7 Claims. (Cl. 57—32)

1

This invention relates to a twine-making machine and more particularly to an apparatus for making multiple strand twine. More specifically it relates to a machine for impregnating the individual surfaces of a plurality of twisted paper strands and in the same operation twisting said strands into multiple strand twine.

A prime object of this invention is to provide an improved means for making multiple strand twine.

Another object is to provide a machine for making paper twine, the individual strands of said twine being individually twisted and then impregnated with a water-resistant material thereby making said twine both flexible and durable.

A further object is to provide an improved machine for impregnating individually twisted paper strands and subsequently twisting said strands into multiple strand twine.

Another object is to provide an improved twine spinning machine, said machine having spinning disks and brake mechanism therefor, the brake mechanism being automatically operable to stop the rotation of said disks upon the breaking of any of the twisted strands or twisted twine.

Other objects will become more readily apparent from the embodiment of the invention which is illustrated in the following description and shown in the accompanying drawings, wherein:

Figure 1 is a side elevational view of a twine-making machine.

Figure 2 is a sectional view taken along the line 2—2 of Figure 1.

Figure 3 is an elevational view of a portion of a braking means for a twine-making machine, said view being taken along the line 3—3 of Figure 1.

Figure 4 is a sectional view taken along the line 4—4 of Figure 1, showing a cover member for a spinning disk.

Referring particularly to Figure 1, a twine-making machine generally consists of a plurality of spinning disks 10 for individually twisting paper strip into paper strands. The twisted strands are guided over a rotating impregnating disk generally indicated by the reference character 11. From the impregnating disks the strands are carried to a twisting guide means 12 where they come together and are subsequently twisted into multiple strand twine by a twisting flyer 13. A braking or cutting-off mechanism for the individual spinning disks 10 is generally indicated by the reference character 14. A drive mechanism 15 is operatively connected to the disks for rotating the same.

2

Each of the spinning disks 10 consists of an annular receptacle 16 which is mounted for rotation on a spindle 17. The spindle 17 is journaled in a bearing 18 mounted on a casing 19 which is carried on a support 20. The lowermost portion of the spindle 17 is keyed to a driven member 21 which operatively engages a driving member 22. The driving member 22 is resiliently held against the driven member 21 by means of a spring 23 and is keyed to a longitudinal drive shaft 24. A divisional application, Serial No. 790,644, was filed December 9, 1947, on the novel features of the spinning disks and the associated structure.

A cover or closure member 25 is positioned above the receptacle and is connected to a bracket 25'. The bracket 25' is pivoted at 26 to a support 27. A former 28 is centrally positioned on the cover member 25 and is journaled with respect thereto in a bearing 29 mounted in the bracket 25'. A twisting finger 30 is screwed to the former 28 for rotation therewith. A cap plate 31 is connected to the bracket 25' for fastening the former 28 and the bearing 29 to the cover 25.

The former 28 includes a vertical bore 32 in axial alignment with a slot 33 of the twisting finger 30. The bore 32 is in communication with a cup-shaped socket 34 formed at the lowermost portion of the former 28.

A pair of radially extending arms 35 are rigidly connected to the former 28 and include radially extending resilient members 36, said members preferably consisting of a spring-like material. The resilient members 36 are adapted to engage

the inner periphery 37 of the receptacle 16 when the cover 25 is in the closed position shown in Figure 2. The spindle 17 is provided at its uppermost end with a conical portion which extends into the receptacle 16 and partially projects into or mates with the cup-shaped portion 34 of the former 28. A support 39 is mounted on the bracket 25' and has journaled thereon a pulley or guide wheel 40.

The impregnating means 11 consists of a rotating disk 41 mounted for rotation about a vertical axis on a shaft 42. A drive means 43 is mounted for rotation about a transverse axis and is adapted to engage the clutch plate 44 thereby imparting rotating movement to the disk 41.

The twisting flyer 13 is of conventional design and is supported at one end by a bracket 45. A bobbin or reel 46 is associated with the flyer 13 for collecting the twisted twine.

The braking or cut-off mechanism 14 is best shown in Figures 1 and 2 and consists of a brake

shoe 46' adapted to engage the outer periphery of the receptacle 16. A bell-crank 47 is mounted for pivotal movement on a support 48. The upper end of the bell-crank 47 is pivotally connected to a rod 49 which is slidably connected to the brake shoe 46'. A collar 50 having a slot 51 is formed integrally with the brake shoe 46 and is adapted to slide along the rod 49. A spring 52 is adapted to normally compress the brake shoe 46 against the external periphery of the receptacle 16. The amount of compression exerted by the spring 52 is adjustable by means of a threaded member 53. The lower portion of the bell-crank 47 is in operative connection with a cam 54 keyed to a longitudinal shaft 55.

Referring to Figures 1 and 3, it can be seen that the longitudinal shaft 55 is keyed to a crank arm 56. The crank arm 56 is in operative connection with a rotating stop 57 which is pivoted about a transversely extending shaft 58. The stop 57 includes a contact element 58'. A drop arm 59 has at its uppermost portion a loop 60 and is provided with a contact member 60'. The multiple strand twine extends through the loop 60 and holds the drop arm 59 in the upright position indicated in Figure 1. Upon breaking of the twine, the drop arm 59 is adapted to rotate about a transverse shaft 61.

A weighted arm 62 is pivotally connected to a bracket 62'. The weighted arm 62 is held in an over-center position by means of a rod 63 slidably carried in supports 64. A shoulder 65 limits the sliding movement of the rod in one direction. A spring 66 encircles one end of the rod 63, said spring being in abutment with one of the supports 64 and a contact member 67 formed at the end of the rod 63. A drop arm 68 is pivotally connected about a transverse axis as indicated at 69, said arm being provided with a loop 71 through which the twisted strands of twine may be guided.

It is, of course, readily apparent that the number of strands used in making the multiple strand twine can vary and is determined by the number of spinning disks used; the present form showing two such spinning disks. The braking means or cut-off mechanism which has been shown is typical for any number of spinning disks used.

Referring particularly to the operation of applicants' machine, a plurality of spinning disks 10 are driven by the longitudinal drive shaft 24. As shown in Figure 2, the paper strip is unraveled from the spool and by virtue of the conical portion 38 of the spindle 17 is guided into the cup-shaped socket 34 of the former 28. The paper is formed in the bore 32 and is thereupon twisted by the twisting finger 30 into individual twisted strands A. Movement of the former and twisting finger is accomplished by the resilient members 36. As can be seen in Figure 2, these resilient members grip the internal periphery of the receptacle 16 when the cover 25 is in the closed position. Thus rotary movement of the receptacle 16 is imparted to the twisting finger and the former.

Each twisted strand is guided over a pulley 40 and over the impregnating disk 41. The impregnating disk is suitably driven about a vertical axis. A dry lubricant or other moisture resisting material such as wax is carried by the impregnating disk, and as the strands A pass over this disk, the peripheral surface of each strand is adequately and efficiently impregnated. The strands A then are carried to the guide means 12 where they are brought together and subsequently

twisted into a finished multiple strand twine B by the flyer 13 as best indicated in Figure 1.

The spring 52 normally tends to lock the brake shoe 46 against the outer periphery of the receptacle. The brake shoe is held away from the spinning disks by means of the stop member 57 which locks the crank arm 56 and the longitudinal shaft 55 against counter-clockwise movement. It is desirable to immediately stop rotation of the spinning disks if at any time the strands A or the twine B should become severed or broken. Provided the strand A is severed, the drop arm 68 will rotate and engage the member 67, pushing said member longitudinally to effect dropping movement of the weight 62. The weight 62 thereupon drops upon the contact element 58' of the stop 57. This causes the stop 57 to rotate thereupon releasing the crank arm 56 and the longitudinal shaft 55 for counter-clockwise movement. The spring 52 thereupon is free to force the brake shoe against the receptacle. Should the multiple strand twine B be broken the drop arm 68 will be free to rotate from its vertical and the contact element 60' will engage the contact element 58' of the release member, thus disengaging the stop member from the crank arm 56.

It can thus be seen that the objects of the invention have been fully achieved in the embodiment disclosed, and it must be understood that various modifications may be made which do not depart from the spirit of the invention as disclosed nor as defined in the appended claims.

What is claimed is:

1. A twine-making machine comprising in combination, a plurality of spinning disks, each of said disks supporting a spool of paper strip, twisting means associated with each disk for individually twisting said strips into twisted strands, impregnating means for impregnating the twisted strands, means for driving said spinning disks, a brake associated with each spinning disk, and means operable to actuate said brake upon the breaking of said twisted impregnated strands.

45 2. A twine-making machine comprising in combination with a twisting flyer and a twisting guide means, a plurality of spinning disks, each adapted to rotatably support a spool of paper strip, twisting means associated with each spinning disk for twisting the paper strip into a twisted strand, each of said strands being guided by the twisting guide means and being twisted by the flyer into multiple strand twine, a brake member for each spinning disk, and a brake control member suspended from each twisted strand, said control member being operable upon the breaking of said strand to actuate each brake for braking the spinning disks.

3. A twine-making machine comprising in combination with a twisting flyer and a twisting guide means, a plurality of spinning disks, each adapted to rotatably support a spool of paper strip, twisting means associated with each spinning disk for twisting the paper strip into a twisted strand, each of said strands being guided by the twisting guide means and being twisted by the flyer into multiple strand twine, a brake member for each spinning disk, a brake control member suspended from the twisted strand, and a second brake control member suspended from the multiple strand twine, each control member being respectively operable upon the breaking of said strand or twine to actuate each brake for braking the spinning disks.

75 4. A twine-making machine comprising in

combination with a twisting flyer and a twisting guide means, a plurality of spinning disks, each adapted to rotatably support a spool of paper strip, twisting means associated with each spinning disk for twisting the paper strip into a twisted strand, each of said strands being guided by the twisting guide means and being twisted by the flyer into multiple strand twine, a brake member for each spinning disk, a brake control member associated with the twisted strand, and a second brake control member associated with the multiple strand twine, each control member being respectively operable by gravity upon the breaking of said strand and twine to actuate each brake for braking the spinning disks.

5. A twine-making machine comprising in combination with a twisting flyer and a twisting guide means, a plurality of spinning disks, each adapted to rotatably support a spool of paper strip, twisting means associated with each spinning disk for twisting the paper strip into a twisted strand, each of said strands being guided by the twisting guide means and being twisted by the flyer into multiple strand twine, a brake member for each spinning disk, and a brake control member suspended from the multiple strand twine, said control member being operable upon the breaking of said twine to actuate each brake for braking the spinning disks.

6. A twine-making machine comprising in combination with a twisting flyer and a twisting guide means, a plurality of spinning disks each adapted to support a spool of paper strip, said disks being mounted for rotation about vertical axes, means for rotating said disks, a twisting means connected for rotation to each spinning disk and adapted to twist the paper strip into a twisted strand, an impregnating disk rotatably mounted, means for rotating said disk, a guide for guiding said strands over said impregnating disk

and to said twisting guide means, a brake for each disk, and means connected to said strand and to said twine, said means being constructed and arranged to actuate said brake for braking said disks upon breakage of said strand and twine.

7. A twine-making machine comprising in combination, a plurality of spinning disks, each of said disks supporting a spool of strip material, twisting means associated with each disk for individually twisting said strips into twisted strands, means for driving said spinning disks, a brake associated with each spinning disk, and means operable to actuate said brake upon the breaking of said twisted strands.
